UNITED STATES PATENT OFFICE.

LEVI S. SHREFFLER, OF ELMIRA, NEW YORK.

IMPROVEMENT IN RAIL-CHAIRS.

Specification forming part of Letters Patent No. 124,226, dated March 5, 1872.

Specification describing a certain Improvement in Joints for Railroad Rails, invented by LEVI S. SHREFFLER, of Elmira, in the county of Chemung and State of New York.

This invention relates to a joint for the rails of a railroad; and it consists in the construction, combination, and arrangement of the parts of which it is composed, as will be more fully explained hereinafter.

Figure 1 is a sectional elevation of my improved joint on the line $x x$ of Fig. 2, showing the form of the rail, the construction of the two sections of the joint, and the clamping-bolt with its nuts. Fig. 2 is a perspective view of the joint and a portion of the two rails.

Corresponding letters refer to corresponding parts in both of the figures.

The necessity for a railroad joint which shall retain the upper and inner surfaces of the ends of the rails at their points of junction in a plane with each other, and, at the same time, afford a sufficient amount of elasticity at that point to prevent the lamination of the ends of the rails, is acknowledged by all railroad engineers; and this invention has for its object the production of such a joint; and it differs from those now in use in that both of the sections of the joint serve as an elastic support for the head of the rail, one of them presenting, at the same time, a smooth upper surface, flush with the upper surfaces of the rails, for the purpose of preventing a jar when the wheels pass the joint; and it further differs from others in that it affords a double bearing for the ends of the rails, one upon the under side of the heads of the rails, and the other upon the lower surfaces of the rails, upon the ties, to which the joints are fastened.

In constructing joints of this character, I use two plates of metal, A and A', the former being of the form shown in the drawing, its lower surface resting upon a tie, to which it is spiked or bolted. From the inner edge of the base of this section there projects an annular web inwardly in such a manner, and at such an angle, as to cause its under surface to rest upon the upper surface of the base of the rail. The vertical portion of this section of the joint extends upward far enough to come in contact with the under surface of the head of the rail, at which point it is reduced in thickness,

and thus a shoulder is formed for the rail to rest upon, while the remaining portion extends further up, and has upon its upper face a wheel-bearing surface, which is flush with the tops of the rails. The section A' of the joint is the same in all respects as the one above described, except that it has not the part which projects above the under surface of the head of the rails. In constructing these sections, it is important that their upper surfaces, or those surfaces upon which the head rests, should be of such height as that, when the rails are placed in them, they (the rails) shall be suspended by their heads resting upon these portions of the joint, while, at the same time, the lower surfaces of the bases of the rails are allowed to come very nearly in contact with the tie, so that, as the wheels of the train reach the point in or between the ends, the weight with which they press upon said rails shall be transferred to the joint-plates, and thus cause them to spring sufficiently to cause the requisite amount of elasticity to prevent the lamination of the ends of the rails, and, at the same time, permit the rails to find a bearing upon the tie in time to prevent the breaking of the plates of which the joint is composed. For securing the rails within the joint, as well as for holding the two sections thereof in proper contact with the rails, a bolt, B, is provided, which passes through the vertical portions of the two sections of the joint, as shown in Fig. 1, its screw-threaded end being provided with two nuts, so that, when the sections of the joint have been screwed up against the web of the rail, so as to retain the inner surfaces of their heads in the same plane or in line with each other, but not so tightly as to prevent the movement thereof caused by their expansion and contraction, the outer nut may be set up firmly against the other or inner one, and thus the parts held in their adjusted position. Upon referring to Fig. 2, it will be seen that, in order to prepare the rails for the upper or wheel-bearing surface of the portion A of the joint, a portion of the head of each is cut away, as shown at D D', the object being to bring the bearing-surface of the joint as near the center of the rails as possible, in order that the wheel may bear freely upon it while passing over the joint in the rails.

One great advantage arising from this method of constructing rail-joints, and one which has not been alluded to, is, that, when it becomes necessary to remove a rail from its place in repairing the line, it is only necessary to remove the two bolts at its ends, and draw out the spikes in the two sections of the joints which it is necessary to remove, and the rail can at once be removed and another one put in its place. It may be desirable in some cases to use this joint without using the projecting portion which serves as a wheel-bearing surface, and in such cases it may be omitted, in which case the necessity for removing a portion of the heads of the rails will be obviated, and all the other features of the joint will remain the same in construction and function.

What I claim as my invention, and desire to secure by Letters Patent, is—

A rail-joint consisting of two sections, A and A', adapted to rest upon a single tie, and a bolt, B, with tightening-nuts, the parts being constructed and arranged substantially as described and shown, as a consequence of which the ends of the rails of the truck are suspended by the contact of the under surfaces of their heads with the upper surfaces of the sections of the joint, and, at the same time, or as soon as the weight is applied to the joint, the rails shall seat themselves upon the tie to which the joint is fastened.

In testimony whereof I have signed my name to this specification in the presence of two subscribing witnesses.

LEVI S. SHREFFLER.
